FLYING FEATHER TOY

Orestes A. Pierce, New York, N. Y.

Application October 19, 1951, Serial No. 252,095

3 Claims. (Cl. 46—80)

1

This invention relates to flying toys and more particularly to a type of toy resembling a flying feather.

It is an object of the present invention to provide a flying toy which resembles a flying feather and which is easy and safe to operate and which will fly through the air in a novel manner.

It is another object of the present invention to provide a flying toy which will fly into the air and as it descends will release a parachutist with novel means for dropping the parachutist to earth.

It is a still further object of the present invention to provide a flying toy which will fly through the air in a manner similar to that of birds.

Other objects of the present invention are to provide a flying toy which is of simple construction, easy and safe to operate, inexpensive to manufacture, pleasing in appearance and efficient in operation.

For a better understanding of the invention, reference may be had to the following detailed description taken in connection with the accompanying drawing, in which:

Fig. 1 is a perspective view of a flying toy embodying the features of the present invention;

Fig. 2 is a fragmentary plan view of the bottom of the flying toy shown in Fig. 1;

Fig. 3 is a fragmentary vertical sectional view taken on line 3—3 of Fig. 2;

Fig. 4 is a fragmentary plan view of the feather parachute, shown in Fig. 1;

Fig. 5 is a fragmentary side view of the feather parachute, taken along lines 5—5 of Fig. 4;

Fig. 6 is a fragmentary vertical sectional view taken on line 6—6 of Fig. 5;

Fig. 7 is a perspective view of the flying toy and parachute assembly of Fig. 1 showing the flight trajectory of the same.

Fig. 7A is a perspective view of a modified form of parachutists and feather parachute.

Fig. 8 is a fragmentary side view, partly in section, showing a modified means for projecting the flying toy into the air;

Fig. 9 is a perspective view of a modified form of the present invention;

Fig. 10 is a plan view of a modified form of feather parachute;

Fig. 11 is an enlarged fragmentary view of the means for joining the feathers together shown in Fig. 9;

Fig. 12 is a perspective view of the flying feather toy with parachutist assembly as held in the hands prior to releasing into the air;

2

Fig. 13 is a perspective view showing the flying feather and parachutist assembly subsequent to projection into the air;

Fig. 14 is a fragmentary perspective view of a modified form of the invention showing a toy bird attached to the flying toy;

Fig. 15 is an enlarged perspective view of the means for retaining the toy bird on the flying feather;

Fig. 16 is a fragmentary vertical section taken along lines 16—16 of Fig. 14;

Fig. 17 is a perspective view of a modified form of clamp for pinching the rubber tubing shown in Fig. 9.

Referring now to Figs. 1 through 7, a flying wing 1 has fixedly connected to the underside thereof a tubular element 2, which lies along the central axis of the flying wing 1 and extends forward of said flying wing 1. The tubular element 2 is fixedly connected to the flying wing 1 by means of the fastening elements 3 and 4. A stabilizing wire 5 extends along the longitudinal axis of the flying wing 1 rearwardly of the tubular element 2 and is fixedly connected thereto by means of a fastening element 6. The front end of the stabilizing element 5 extends forwardly of the fastening element 6 and is fixedly connected to the rear of the tubular element 2 in conventional manner by means of the loop 7. Housed within the tubular element 2 is a rubber band 8, which is fixedly connected in the conventional manner to the inner rear end of the tubular element 2. This rubber band 8 is fixedly connected to a finger loop 9 by means of a tubular fastening element 10.

A toy parachutist 11 is made of flat cardboard or metal with the weight so distributed that the parachutist 11 will remain in a vertical position when dropped from a height. This toy parachutist 11 is connected by means of a cord 12 to a circular disc 13. To the upper surface of this circular disc 13 are fixedly connected three feathers 14, 15 and 16, angularly spaced from each other as shown in Figs. 1 and 4. A wire loop 17 is fixedly connected to the circular disc 13 at one end and adapted to detachably engage a vertically extending wire 18 provided in the upper front surface of the flying wing 1, as shown in Fig. 1.

The stabilizing element 5 is curved downwardly at the rear end thereof in order to impart the flight characteristics to the flying wing illustrated in Fig. 7. The flying wing and parachutist assembly are projected into the air in the manner shown in Fig. 1, the thumb of the left hand en-

gaging the finger loop 9 while the thumb and first finger of the right hand engage the rear curved surface of the flying wing 1; thus stretching the rubber band 8 to its maximum. Upon releasing the rear end of the flying wing 1, the entire flying toy including the parachutist and feather parachute are projected into the air in the manner shown in Fig. 7. As the flying wing begins to descend, the parachutist and feather parachute are released and the parachutist 11 descends slowly to the ground, the feather parachute due to the pitch of the feathers executing a descending spiral as is shown in Fig. 7. In the different figures, like parts are given in certain instances the same numerals.

In Fig. 7A, there is shown a modified form of the feather parachute, and parachutist. The parachutist 19 is constructed of thin light material such as plastic, while the feet therefor are made of lead in order to insure the vertical position of the parachutist upon landing. The parachutist 19 is connected by means of the cord 12 to a feather parachute comprising a series of upwardly concave feathers so connected together at their lower ends so as to produce substantially a hemispherical surface as shown in Fig. 7A. A loop 21 of aluminum or other light material is connected to the center of the hemispherical feather surface by means of a cord 12. This loop 21 engages the upwardly extending wire 18 of the flying wing 1 in a manner similar to that of the wire 17, shown in Fig. 1. The operation of this modified form of the parachutist and feather parachute is similar to that of the feather parachute shown in Fig. 1 with the exception that the descending flight characteristics of the parachute are different. Upon returning to earth, the parachutist 19 and the hemispherical feather mass 20 descend vertically, the hemispherical feather mass 20 spinning on its central axis.

In Fig. 8, there is shown a modified form of the means for projecting the flying wing 1 into the air. The tubular element 2 is connected to the flying wing 1 by means of the fastening element 22. This fastening element 22 may be made of rubber or any other suitable material. A rubber band 8 is connected in the conventional manner to the inner rear end of the tubular element 2 and extends downwardly through the tubular element 2 and through the flying wing 1 by means of the opening 23. The rubber band is then brought around the lower surface of the fastening element 22 and looped over the tip of the thumb of the left hand. The rubber band is then extended by pulling back the flying wing 1 in a manner similar to that shown in Fig. 1.

In Fig. 9, there is shown a modified form of the present invention consisting of two feathers 24 and 25 connected together by means of a short tubular piece of rubber 26. At the center of this rubber tubing is a metallic clamp of malleable metal 27 which pinches the central part of the rubber tubing 26. The metallic clamp 27 imparts to the rubber tubing 26 a slightly V-shape. The pinching of the rubber tubing 26 into a slightly V-shaped element imparts remarkable flight characteristics to the flying toy itself. At the ends of the rubber tubing are looped two rubber bands 8. The central section of the fastener 27 is bent upwardly on one side as shown in Fig. 11 to provide a hooked member, 28.

Referring to Figs. 10 and 12 there is shown a modified form of parachutist and feather parachute. A circular disc 13 has fixedly connected to the upper side of the surface thereof a para-

chutist 29 and three feathers 30, 31 and 32. These three feathers 30, 31 and 32 are curved downwardly along their major axes and are connected to the disc 13 in the manner shown in Figs. 10 and 12. A wire loop 17 is fixedly connected to the disc 13 at one end and adapted to detachably engage the hooked member 28 at the other end, as shown in Fig. 12.

In operation, the rubber bands 8 are looped over the upper part of the thumb of the left hand and the two feathers 24 and 25 are bent back upon each other in the manner shown in Fig. 12, the thumb and first finger of the right hand grasping the juxtaposed ends of the feathers; the rubber band is extended and upon releasing the outer ends of the feathers 24 and 25, the flying feather and parachutist assembly are projected into the air in the manner shown in Fig. 13. As the flying toy ascends into the air the parachutist assembly is released and spins to earth in a helical manner. The flying feather toy itself returns to earth with the wings fluttering in the manner indicated in Fig. 13. By increasing the bending effect of the fastening element 27 the flight characteristics of the flying feather may be changed so that the feathers actually rotate instead of fluttering.

In Fig. 14, there is shown a modified form of the flying feather shown in Fig. 9. A toy bird 33 is fixedly connected to the center of the rubber tubing 26 by means of a fastening element 34. This fastening element is shown in greater detail in Fig. 15 and comprises a lower part 35 and 36 which serves to pinch the rubber tubing in a manner similar to that of the fastening element 27 and an upper portion 37 and 38 which retains the bird in its position. In Fig. 14 there is shown only one rubber band 8. The feathers 24 and 25 are folded back upon each other in a manner similar to that in Fig. 13 and the rubber band 8 is looped over the upper part of the thumb of the left hand while the thumb and first finger of the right hand stretch the rubber band by gripping the ends of the juxtaposed feathers 24 and 25. Upon release the flying feather toy with the bird assembly is projected into the air and executes a course similar to that shown in Fig. 13.

In Fig. 17, there is shown a modified form of fastening element comprising a piece of metallic malleable metal bent into a U-shape. This fastening element 39 serves to bend the rubber tubing 26 at the desired angle and is employed when it is not desired to attach a parachutist assembly.

It should now be apparent that there has been provided a flying toy which is easy and safe to operate and which employs novel means of imparting flight to the flying toy as well as including novel performance characteristics.

While various changes may be made in the detailed construction, it should be understood that such changes shall be within the spirit and scope of the present invention, as defined by the appended claims.

What is claimed is:

1. A flying toy comprising two feathers, a rubber tubular element, said rubber tubular element being fixedly connected to the feathers at each end thereof, a fastening element fixedly connected to said rubber tubing at the central portion thereof whereby to impart a slight bend to said tubular element, said fastening element being provided with a hook on the upper portion thereof, two rubber bands fixedly connected to the outer ends of said rubber tubular element, and a parachutist assembly detachably connected

to said hook, said parachutist assembly comprising a flat circular disc, a toy parachutist connected to the upper surface of said circular disc and extending vertically therefrom and three vertically extending feathers fixedly connected to the upper surface of said circular disc at the periphery thereof and at right angles to each other, said feathers curving downwardly along the longitudinal axes thereof.

2. A flying toy comprising two elongated feathers, said feathers having longitudinal stems which are curved, a tubular element of rubber, the ends of said tubular element being fixedly connected to the ends of said curved stems, a U-shaped element of malleable metal fixedly connected to the center of said tubular element whereby to bend same into a slightly V-shape and rubber bands fixedly connected to the ends of said rubber tubing element.

3. A flying toy comprising two elongated feathers, said feathers having longitudinal stems which are curved, a rubber tubular element, the ends of said rubber tubular element being fixedly connected to the ends of said stems, a U-shaped fastening element of a malleable metal fixedly connected to the central portion of said tubular element whereby to pinch and bend same into a slight V-shape, the central portion of said V-shaped element being bent upwardly on one side whereby to provide a hook, a parachutist as-
